UNITED STATES PATENT OFFICE.

BENJAMIN F. BAIN, OF PITTSBURGH, PENNSYLVANIA.

MECHANICAL TOY.

1,264,256.

Specification of Letters Patent. Patented Apr. 30, 1918.

Application filed August 30, 1917. Serial No. 189,023.

To all whom it may concern:

Be it known that I, BENJAMIN F. BAIN, a resident of Pittsburgh, in the county of Allegheny and State of Pennsylvania, have 5 invented a new and useful Improvement in Mechanical Toys, of which the following is a specification.

This invention relates to toys. The mechanism involved is particularly designed to 10 simulate in a miniature way a windmill operating a well pump.

The objects of the invention comprise 15 making a device which may be operated by a current of air against the vanes of the windmill, or by hand through an ordinary pump handle arrangement. In the latter case, the windmill is itself actuated by the pump mechanism. Another object is to furnish a device which will discharge sand or 20 other flowing material through a spout in such manner as to closely simulate the discharge of water from a well pump. Another object is to actuate a valve controlling the flow of sand, or any other suitable material, 25 from a reservoir to the spout, and to operate it by connection to the pump mechanism, in such manner as to allow the material to run out in a way to closely simulate the discharge of water from an actual well pump 30 of the same type as that here provided in miniature form. Another object is to provide a rigid frame construction for the toy, so that certain parts of it may be readily assembled for use, and disassembled for packing 35 in compact form. Other advantages of the construction shown and described will more fully appear throughout the following specification, and will be obvious to those familiar with such devices.

40 Referring to the drawings, Figure 1 is a side elevation of the complete toy; Fig. 2 is a front elevation; Fig. 3 is a partial section and elevation of the side of the pump opposite to that of Fig. 1; and Fig. 4 is a 45 plan view.

In the construction of toys having movable parts, and intended to simulate in operation large commercial machines, it is desirable that the toy have the same general 50 appearance as the actual machines. But it is also necessary that the construction of the toy be simple, that is, that it shall have as few movable parts as possible consistent with the main objects, and that these parts 55 shall be assembled in such manner as to give maximum economy of material and

labor. Furthermore, the parts must be so constructed that the whole device can be quickly assembled by comparatively unskilled persons, and of such form that they 60 may be made and shaped so far as possible by machinery. The present toy combines these desirable features to a high degree.

It consists of a sheet metal base 1 having a raised edge or flange 2 on all sides, for 65 stiffening and fastening purposes and adapted to set on any flat surface. In opposite sides of this base pan are small holes adapted to engage hooks 3 at the lower ends of upright members 4 and 5. These uprights 70 are formed of single pieces of wire converging to horizontal portions 6 and 7, respectively, at the top, and have at each end one of the outwardly bent hooks 3, adapted to pass through and be engaged by the holes 75 in the sides 2 of base member 1. The supports 4 and 5 are made of resilient material, and are of sufficient width at the bottom to press normally outward against the sides of the base 1. The hooks are engaged in the holes of said base member by 80 springing the ends of the supports inward sufficiently to bring the hooks inside the side walls of the base, and then by releasing the pressure, the hooks pass out through the 85 holes, and are firmly engaged therein. This furnishes a ready method of assembling or disassembling the supports and base. Suitable cross girders 8 are provided to reinforce the uprights 4 and 5, and also to connect them to each other at two or more points, in order to form a rigid derrick for supporting the windmill and reservoir, 90 below described. A pump stock 9, preferably wooden, is secured to the base 1 by a screw 95

10. This stock has a lateral spout 11, slanting connecting with a central bore 12, extending upward from the spout to the top of the pump stock. In this bore is fitted a pipe 13, which extends upward to an 100 enlarged funnel-shaped terminal 14. This terminal is situated just beneath the outlet 15 of a storage reservoir 16, supported by and connected to the derrick frame. The outlet 15 from the reservoir 16 is a comparatively small opening, and in the embodiment illustrated, is controlled by a swinging gate valve 17, pivoted on a pin 18 extending through the walls of the reservoir and through wings 19 pressed up from the 110 metal sheet forming the gate valve 17. The funnel-shaped terminal 14 is attached to

the reservoir 16 by a projecting lip 19^a, and a rivet 20 extending through the lip 19^a and the wall of reservoir 16. This part may be connected in any other suitable manner. 5 The metal sheet forming the valve 17 has a rearward extension 21, which is cut away in the middle for the purposes below described. See Figs. 1, 2 and 3. By this construction the valve is readily opened by lifting the extension 21 to the position shown in Fig. 3.

A truss, or supporting member, 22, is made of a single sheet of metal. It is attached to the frame of the derrick and to 15 the pump stock by suitable projections 23. Extending up from each side of this truss are ears 24 with holes therethrough for the passage of a pin 25. A pump handle 26 is pivotally carried by the pin 25, between the 20 ears 24.

One end of the handle 26 is free, the pin 25 acting as a fulcrum for the lever formed by this handle, and the other end is attached by pin 27 to a flattened head 28, at the lower 25 end of a vertical pump rod 30, which has at its upper end a similar head 31. This head 31 is perforated to engage a crank pin 32 riveted into a large gear wheel 33, the teeth 34 of which mesh with the teeth 35 of a smaller 30 gear wheel 36. The latter gear wheel is fixed on a shaft 37. To the other end of this shaft is attached the windmill propeller 38, comprising four or more blades 39. The pump rod 30 has an intermediate flattened 35 portion 40, through which a cross bar 41 is passed, the bar making a tight fit so as to be rigidly carried. The flattened portion 40 is so situated as to be normally positioned in the notch 22 between the horizontally projecting tongues 21 of the valve member 17. 40 The cross bar 41 is normally slightly below the horizontal members 21, but is adapted to engage said members when raised.

The propeller shaft 37 is carried by the 45 upturned ends of a sheet metal member 29, the base of which has its edges 41 turned under to form flanges engaging a sheet metal member 42 which forms by means of upturned lips 43, at its middle portion, the support for the shaft 44 of main gear wheel 33. The other end of the supporting member 42 is turned vertically upward, just beyond its seat upon the upright member 4, to form a tongue 45. A guide vane 46 composed of a 50 flat metal sheet of any desired shape, has riveted to its inner end a sheet metal member 47, bent to form a sleeve 48 adapted to fit snugly over the tongue 45. By this construction the guide vane is readily placed 55 in position and removed, by slipping the sleeve 48 over the vertical tongue 45.

Riveted to the bottom of frame member 42 is another sheet metal member 49, the ends of which are bent downward and then 60 horizontally outward, to form a resilient 65

clamp to hold the frame member 42 securely upon the supports 6 and 7.

It will be evident that by the construction above-described the frame member 42 and the parts carried thereon can be readily removed from the derrick by first releasing the frame members 42 and 49 by turning them diagonally between the horizontal supports 6 and 7 and then disconnecting pump rod 30 from the crank pin 32 of the gear 75 wheel 33. In order to hold the frame securely in proper position, the under side of support members 6 and 7 have flattened or cut-away portions 50, adapted to engage the 80 ends of member 49.

It will be observed that the outer end of the crank pin 32 is turned up in such a way as to permit its easy entrance into the hole in the end of pump rod 30 and yet to prevent its disconnection when the toy is in operation, and consequently the engagement of the two parts is locked for all practical purposes, though subject to ready disengagement for disassembling.

The operation of the device is as follows: 90 By manually moving the outer end of pump handle 26 up and down, the pump rod 30 is reciprocated and drives the wheel 33 and consequently the windmill propeller, giving the appearance of an active windmill pump. 95 As the pump rod 30 moves up and down, near the upper limit of its travel the cross bar 41 engages the extensions 21 of the valve 17, moving it into the position shown in Fig. 3, and for an instant opening the valve and 100 permitting discharge of a small amount of sand or other suitable material from the reservoir 16. As soon as the cross bar moves down a short distance the valve is closed by gravity and the flow cut off. This 105 results in material being discharged through the spout 11 in a manner suggesting the effect of an ordinary windmill pumping water. The reservoir is designed to contain enough material to supply it in this 110 manner for a considerable time.

Another method of operating the device is to turn the windmill propeller toward a current of air, such as an ordinary breeze out of doors, one from an electric fan, or one 115 caused by blowing directly upon the propeller vanes. This drives the windmill, and consequently operates the pump without manipulation of the lever 26.

While sand or similar dry material is preferred for simulating the flow of water from the pump spout, any other flowing substance or material may be used,—appropriate changes being made in the valve to adapt it to the particular flowing substance which is 125 to be used.

The device furnishes a very interesting toy, and one which is mechanically instructive. It has no parts that will easily get 130 out of order, and the simplicity of construc-

tion renders it economical to manufacture. It may be packed in a comparatively small space, and the frame is rigid enough to stand shipment when properly packed without danger of breakage.

5 I claim:—

1. A toy comprising a windmill, a pump rod operated by the windmill, a reservoir for flowing material, an outlet beneath the reservoir, and a valve controlling said outlet adapted to be operated by reciprocation of the pump rod.

10 2. A toy comprising a windmill device, a vertical rod adapted to actuate the windmill, a device simulating a pump, a lever simulating a pump handle having one end attached to the rod actuating the windmill, a reservoir adapted to contain a flowing material, a valve controlling an outlet from the reservoir, and means to actuate the valve to release material from the reservoir to the pump by movement of the pump handle.

15 3. A toy comprising a pump stock, a spout therefrom, a pump handle, a reservoir for flowing material, and a valve controlling an outlet from the reservoir to the pump stock adapted to be actuated by movement of the pump handle to release material from the reservoir through the pump spout.

20 30 4. A toy comprising a windmill device, a pump rod adapted to be actuated thereby, a reservoir for flowing material, a valve controlling an outlet from the reservoir, means to actuate the valve by movement of the

pump rod, and a pump stock and spout below the reservoir through which the material is discharged when released from the reservoir.

5 5. A toy comprising a pump stock, a spout therefrom, a pump handle, a pump rod attached to the pump handle, a windmill device connected to the other end of the pump rod, a reservoir for flowing material, a valve controlling an outlet from the bottom of the reservoir, and an operative connection from the valve to the pump rod, whereby when the pump handle is actuated, the windmill is turned and material is discharged from the reservoir through the pump stock.

10 6. A toy comprising a pump stock, a spout therefrom, a pump handle, a pump rod attached to the pump handle, a windmill wheel connected by gears and a crank to the upper end of the pump rod, a reservoir for flowing material, a valve controlling an outlet port from the reservoir, a connection from the reservoir outlet to the pump spout, and means to open the valve at the upper limit of travel of the pump rod, whereby when the windmill wheel is actuated, material from the reservoir is discharged through the pump spout.

15 In testimony whereof, I have hereunto set my hand.
